HENRI FRANÇOIS LOUIS JOSEPH ROCHERON, OF LEVALLOIS-PERRET, FRANCE

FASTENING DEVICE FOR DOORS

Application filed July 10, 1930, Serial No. 467,108, and in France September 11, 1929.

My invention relates to a fastening device for doors and other similar parts.

This device is chiefly intended to be used in connection with the doors of automobile bodies which are submitted to rapid deformations on account of the play between the different parts of the body.

My device comprises a lug and a socket member which are adapted to be mounted 10 opposite each other on the parts to be secured together respectively, for instance one of them on the door and the other on the door frame of an automobile body, so that, when the door is being closed, the lug engages the 15 socket member, in order, not to ensure the locking of the door, but to elastically attenuate the vertical vibrations of this door and thus to relieve the hinges.

My invention is characterized in that, on 20 the one hand, the socket member comprises a clip the jaws of which are articulated together about a member integral with said socket member, for instance an axis, and are pressed toward each other by elastic organs, 25 such as rubber blocks, springs or the like, whereas, on the other hand the lug, which is adapted to slide longitudinally between the jaws of the clip, is substantially wedge-shaped, so as to progressively move the jaws 30 of the socket member apart from each other as said wedge-shaped lug penetrates between them.

Owing to this disposition, the jaws of the 35 socket member constantly hold the wedge between them from the time said wedge is being forced between them by the closing of the door. This door is thus elastically held in position, whatever be the play in its fitting. It should be remarked that, owing to the fact that the jaws of the socket member are articulated to a fixed part of the socket member, the elastic organs exert a regular and constant pressure on either side of the 45 wedge through said jaws, so as to always keep said wedge in their median plane.

An embodiment of my invention will be described with reference to the appended drawings in which:

50 Fig. 1 is an elevation of the socket member

as mounted on the door frame of an automobile body;

Fig. 2 is an end view of said socket member;

Fig. 3 is a side view of said socket member;

Fig. 4 is a section of the socket member on the line 4—4 of Fig. 1.

Fig. 5 is an elevational view of the back face of the wedge support, the wood of the door casing being partially cut away so as to show that piece.

Fig. 6 is a side view corresponding to Fig. 5.

The socket member (Figs. 1 to 4) comprises a casing 1, closed by a plate 2 which is screwed thereon by means of screws 3. A clip comprising two jaws 4 and 5, is mounted in the middle part of the casing so that the interval between the jaws may register with an opening 6 (Figs. 3 and 4) provided in plate 2 and casing 1. The jaws 4 and 5 of the clip are pivotally mounted on an axis 7 integral with a projecting part 8 of the casing. Said jaws each have a raised edge 9 for ensuring a good hold on the wedge.

On opposite sides of jaws 4 and 5 are disposed two rubber blocks 10 enclosed between the walls of casing 1, plate 2 and the two jaws 4 and 5. These blocks, owing to their elasticity, will force the jaws toward each other, by causing them to pivot about their stationary axis 7.

A stop 11 (Figs. 1 and 4) integral with jaw 5 and adapted to come into contact with jaw 4 maintains a minimum distance between said jaws. Holes 12 are provided in casing 1 and plate 2 so as to make it possible to secure the socket member to the door-frame of the automobile body or any other suitable structure.

Wedge 13 (Figs. 5 and 6), which is of a substantially triangular longitudinal section, is integral with a plate 14 provided with holes 15 for securing it to the door.

When the device is to be mounted, the socket member being secured for instance to the door casing of the body, the wedge is so disposed on the door that, when said door is shut, the wedge, entering the opening 6 of the keeper, may slide longitudinally between

jaws 4 and 5 of the clip, the tapering part 16 of the wedge being the first to come into contact with said jaws. As the wedge is being moved forward, the jaws are pushed apart in a symmetrical way owing to their being pivotally mounted on a fixed basis 7 and then compress the rubber blocks 10. The reaction of these blocks on the wedge 13, through the intermediary of articulated jaws 4 and 5, ensures the elastic securing of the door whatever be the play that may be present in the fitting of said door.

While I have disclosed what I deem to be the preferred form of my device I do not wish to be limited thereto as there might be changes made in the construction disposition and form of the parts without departing from the spirit of my invention as comprehended with in the scope of the appended claims.

20. What I claim is:

1. A device for the elastic fastening of a door to its frame comprising a casing adapted to be fixed on one of the elements to be fastened together, an axis in said casing, two jaws pivotally mounted on said axis, elastic means for pushing said jaws toward each other, a plate adapted to be fixed on the other element, a wedge on said plate for engaging the jaws mounted in the casing, whereby the two elements are elastically fastened together.

2. A device of the elastic fastening of a door to its frame comprising a casing adapted to be fixed on the frame, an axis in said casing, two jaws pivotally mounted on said axis, elastic means for pushing said jaws toward each other, a plate adapted to be fixed on the door, a wedge on said plate adapted to be pushed between the jaws when the door is shut, whereby the door is elastically secured to the frame.

3. A device for the elastic fastening of a door to its frame comprising a casing adapted to be fixed on the edge of the door-frame, an axis in said casing, two jaws pivotally mounted on said axis and extending transversely with respect to the door-frame, rubber blocks inserted in said casing for pushing said jaws toward each other, a stop on one of said jaws adapted to come into contact with the other jaw so as to maintain a minimum space between said jaws, a plate adapted to be fixed on the edge of the door, a wedge on said plate extending transversely with respect to the door and located at the level of the space between the jaws, so as to slidily engage said jaws when the door is shut.

In testimony whereof I affix my signature.

HENRI FRANÇOIS LOUIS JOSEPH ROCHERON.
